APPLICATOR

Lewis Franklin Bonham, North Plainfield, N. J.,
assignor to The Personal Products Corporation,
New Brunswick, N. J., a corporation of New
Jersey

Continuation of application Serial No. 342,895,
June 28, 1940. This application June 18, 1943,
Serial No. 491,361

3 Claims. (Cl. 128—263)

1

This invention relates to medical applicators and more particularly to an applicator especially adapted to contain and provide for the insertion of a tampon into a body cavity. This applicator is a continuation of my co-pending application Serial No. 342,895 for Improvements in applicators filed June 28, 1940, and now abandoned.

It is an object of this invention to provide an improved sanitary, single-use tampon applicator, which may also be used as a container and which facilitates insertion of a tampon into the vagina or other body cavity without injury or discomfort and without the user's hands touching either the tampon or the body.

Other objects and advantages of this invention will be apparent from the following description when read in connection with the drawings in which:

Figure 1 is a longitudinal section taken through the center of an applicator and illustrating a tampon positioned in the applicator prior to expulsion; and

Figure 2 is a similar view illustrating the tampon expelled from the applicator.

Referring to the drawings, the applicator of this invention is composed of a tube or container 1 formed of relatively stiff cardboard or other suitable material, as is common in this field. Cardboard is preferred and is particularly suitable because it is sufficiently rigid, safe, and noninjurious in use as distinguished from metals, glass, and similar substances and is particularly suitable for single-use applicators, being inexpensive. The tube is cylindrical in cross section, of proper diameter to snugly receive and frictionally hold a tampon 3, and is approximately twice the length of the tampon or suitable length to permit ready manipulation of the applicator without the user's fingers contacting the body, and becoming soiled and without the tampon being engaged and becoming unsterile. The discharge end of the tube is unrestricted, i. e., of the full diameter of the tube to permit free discharge of the tampon, whereas the other end of the tube is crimped as at 5 to form a restricted opening of proper diameter to slidily receive and guide a tubular plunger 7 for axial movement relatively to the tube 1.

Plunger 7 is of considerably less diameter than the tube 1 but of sufficient diameter to provide necessary rigidity to the plunger and to receive the withdrawal cord of the tampon, which cord also serves to guide the inner end of the plunger. The plunger 7 is also preferably formed of paper and is of approximately the same length of tube 1, i. e., sufficiently long to expel the tampon from

the tube. Both ends of the plunger 7 are beaded or rolled to provide beads or flanges 9 of somewhat greater diameter than that of the restricted opening in the one end of tube 1. The flange 9 on the inner end of the plunger acting in cooperation with the restricted opening formed at 5 interlocks the plunger to the tube whereby withdrawal of one of the two members from the vagina or other body cavity also will cause removal of the other member. Flanges 9 also insure that the two elements will not become disengaged during packaging and shipping and eliminate the necessity of any assembly on the part of the user prior to actual use. The tube and plunger are assembled in the first instance by forcing the plunger into and through the restricted end 5 of the tube from the restricted end. The formation of the crimped end 5 and the character of the material permits this being done by permitting the end wall to be forced inwardly slightly toward the distant end of the tube as shown in the drawings with the result that the restricted opening through the end wall or flange lies slightly inwardly from its end of the outer tube. This construction also prevents subsequent separation of the two elements unless separation is deliberately forced. The crimped end 5 because of the smaller diameter of the plunger 7 also provides a guide for the plunger which guide permits angular or radial movement of the plunger relatively to the tube 1 as well as axial movement as described previously, thus preventing binding or locking of the two tubes if the plunger is not moved by the user in a direction exactly in coaxial alignment with the tube. Flanges 9 also serve two other functions in that the inner flange 9 provides a greater contact area of the plunger against the tampon and therefore reduces the tendency to mutilate the tampon when being expelled. Similarly, flange 9 upon the outer end of the plunger which is engaged by the finger of the user, provides a more comfortable contact end for the user.

In use the applicator with a tampon therein as shown in Figure 1 is inserted into a body cavity such as the vagina for a short distance to a point beyond the sphincter muscle after which the plunger 7 is pushed inwardly with respect to the tube 1 thus expelling the tampon into the vaginal cavity. After the tampon is free from the containing tube 1 the tube and plunger may be removed by withdrawing, it being only necessary to withdraw either the plunger or the tube, i. e., it is not necessary for the user to grasp both the tube and the plunger.

Forming the plunger substantially smaller than

2

the containing tube not only eliminates any friction or binding between the tube and plunger, thus making insertion of the tampon easier, but also eliminates any possibility of the delicate side walls or tissues of the vagina or other cavity being pinched or torn by being caught between the sides of the tube and plunger and tube.

Other advantages will be apparent to those skilled in the art to whom it will also be apparent that minor changes may be made in the details of construction without departing from the spirit and scope of the invention as defined in the appended claims.

I claim:

1. A single-use tampon applicator comprising a thin walled tube adapted to receive and hold a tampon in one end thereof, said tube being flanged inwardly at its other end to provide a yielding end wall having a restricted opening at said latter end and a tubular plunger of substantially less diameter than said tube so as to be freely movable therein projecting into said tube through said restricted opening, said plunger having a flange of greater diameter than said restricted opening upon its end lying within said tube to prevent accidental removal therefrom and being guided by the edges of said restricted opening for sliding and angular movement within said tube whereby a tampon positioned in said tube may be expelled therefrom by movement of said plunger into said tube.

2. A combined container and applicator for an internal catamenial device of the type consisting of a compressed core of absorbent material, an elongated paper tube of a diameter to releasably receive said core therein, another paper tube par-

tially within said first named tube with one of its extremities in engagement with said core, and a conical spacer flange integrally in-turned on one of said tubes to telescopically receive and engage the other of said tubes to maintain said tubes in substantially uniform spaced relation.

3. A single use tampon applicator comprising a paper tube of sufficient internal diameter to receive and releasably hold a tampon in one end thereof, said tube being flanged inwardly at its other end to provide an integral yielding end wall, said end wall having a restricted opening there-through positioned inwardly from said latter end of the tube, and a plunger of substantially less diameter than said tube, projecting into said tube through said restricted opening, said plunger being guided by the edges of said restricted opening for sliding and angular movement within said tube and being of sufficient length to engage a tampon positioned in said tube and expel the tampon from the tube by movement of said plunger into said tube.
